UNITED STATES PATENT OFFICE.

GEORGE B. BEIDERHASE, OF NEW YORK, N. Y., ASSIGNOR TO JOSEPH FAHYS & CO., OF NEW YORK, N. Y., A CORPORATION OF NEW YORK.

DESIGN FOR A BOTTLE.

42,431.

Specification for Design.

Patented Apr. 30, 1912.

Application filed July 23, 1910. Serial No. 573,587. Term of patent 7 years.

To all whom it may concern:

Be it known that I, GEORGE B. BEIDERHASE, a citizen of the United States, and a resident of New York city, borough of Manhattan, in the county of New York and State of New York, have invented a certain new, original, and ornamental Design for Bottles, of which the following is a specification.

In the accompanying drawing, Figure 1 is a top plan view of a bottle, and Fig. 2 a view in side elevation thereof, showing my design.

I claim:

The ornamental design for a bottle, as shown.

GEORGE B. BEIDERHASE.

Witnesses:

H. B. O'BRIEN,
C. R. WOODWARD.
